UNITED STATES PATENT OFFICE.

SOLON OWEN CAMPBELL, OF VAN WERT, IOWA, ASSIGNOR OF TWO-THIRDS
TO ADAM J. JOHNSON AND JOHN GEMMILL, BOTH OF SAME PLACE.

MAIL-BAG.

SPECIFICATION forming part of Letters Patent No. 295,733, dated March 25, 1884.

Application filed January 25, 1884. (No model.)

To all whom it may concern:

Be it known that I, SOLON O. CAMPBELL, a citizen of the United States, residing at Van Wert, in the county of Decatur and State of Iowa, have invented certain new and useful Improvements in Mail-Bags; and I do declare the following to be a full, clear, and exact description of the invention, such as will enable others skilled in the art to which it appertains 5 to make and use the same, reference being had to the accompanying drawings, and to the letters and figures of reference marked thereon, which form a part of this specification.

This invention relates to certain new and 15 useful improvements in mail-bags; and it consists in a combined fastening and tag-holder, whereby the bag is fastened and the tag-holder securely held in place on the bag, as will be hereinafter more fully described, and then specifically pointed out in the claims.

In the annexed drawings, which fully illustrate my invention, Figure 1 is a perspective view of my improved bag-fastening and tag-holder, showing the bag closed, locked, and 25 labeled, and ready for transportation. Fig. 2 is a plan view of the hinged fastening or locking-frame, showing the same opened or distended. Fig. 3 is a plan view, showing the hinged frame closed. Fig. 4 is a side view of 30 the hinged frame. Fig. 5 is a detailed sectional view of the tag-holder and frame. Fig. 6 is a detail view of the tag-holder.

The letter A indicates a hinged metal frame, consisting of four pieces, *a a a' a'*, hinged to each 35 other at their ends, so as to form a rectangular opening, to which the mouth of the bag is attached. Two of the pieces, *a' a'*, are shorter than the others, *a a*, as shown in Fig. 2, and consist of plain flat bars of metal, preferably extended 40 below the hinges a short distance, to which extension the mouth of the bag is attached without interfering with the action of the hinges, as shown in Fig. 5.

a a are the longer pieces or bars of the frame 45 A, and are provided with hinges at each end to engage with the hinges on the short bars *a' a'*, the hinges being joined by rivets or pins. Each piece *a* is provided with a lip or flange, *b*, at the top, intended to cover the short bars 50 *a' a'* when the frame A is closed. Each lip or flange *b* terminates at one end in a diagonal

line, (see Fig. 2,) so that when the frame is closed the bars *a a* meet in a diagonal line or joint, as shown in Fig. 3, completely covering the short bars *a' a'*. The long pieces *a a* may 55 also have an extension or flange below the hinges for the purpose of riveting the bag to.

c c are short projections or blocks, approximately triangular in shape, formed on the upper side of each lip *b*, at the diagonal end of 60 the same, the purpose of which blocks will be hereinafter explained. The pieces *a a* are each provided with a hole, *b'*, under the diagonal part of the lip *b*, as shown. These holes *b' b'* register or form one continuous opening 65 when the frame is closed. Through the hole so formed the bow of a padlock, C, is passed to lock the frame.

B represents the tag or label holder or case, which is hinged to the flange *b* of one of the 70 long pieces *a* of the frame, and is held in place, face upward, by means of the padlock C, which fits closely over and around the holder and locks the frame when the bag is closed, as shown in Fig. 1. This tag-holder B is provided with a slotted recess, *d*, for the reception of a label 75 or tag, on which the destination of the bag is marked, the slot *e* in its face enabling the tag or label to be seen and read. The opening or slot *e* in the face of the holder is not as wide 80 as the recess *d*, as clearly shown in Fig. 6, thus leaving a flange in the side walls at the top, which prevents the label from falling out and keeps the same securely in place. The holder B is provided with an extension or lip, *f*, which 85 rests on the blocks *c c* when the frame is closed, as shown in Fig. 5. These blocks thus form a stop or guard, which prevents the label from slipping out or being removed when the frame is locked.

When the mail-bag has arrived at its destination, the padlock is unlocked and removed from the frame A, thus permitting the holder or case B to be turned back on its hinge, with its face resting on the flange *b*, (see Fig. 3,) 95 when the label may be easily removed and another one inserted, if desired.

A staple and ring, *g*, on the piece *a*, opposite the piece to which the tag-holder is hinged, serves as a handle to open the mouth of the 100 bag, or rather the frame, the tag-holder itself serving a like purpose.

It may be remarked that the padlock C serves the double purpose of locking the bag-frame and at the same time holding the tag-case, face upward, in place on the frame. By this device 5 the label is always in position to be read, and cannot be tampered with.

Having thus described my invention, what I claim as new, and desire to secure by Letters Patent, is—

- 10 1. In a combined mail-bag fastening and tag-holder, the combination of the frame A, composed of hinged sections, two of which are perforated for the passage of a padlock, a tag-holder, B, pivoted to the top of one of said sections, and a padlock, C, passed through the 15 closed frame, so as to secure the same and con-

fine one end of the tag-holder, substantially as described.

2. In a combined mail-bag fastening and tag-holder, the combination of the side pieces, *a a*, 20 having flanges *b b*, apertures *b' b'*, and blocks *c c*, the end pieces, *a' a'*, the tag-holder B, hinged to one of the side pieces, and having lip *f*, and the padlock C, substantially as described.

In testimony whereof I affix my signature in 25 presence of two witnesses.

SOLON OWEN CAMPBELL.
